ATTORNEY

UNITED STATES PATENT OFFICE.

GEORGE BELL, OF WILKINSBURG, PENNSYLVANIA, ASSIGNOR TO WESTINGHOUSE ELECTRIC & MANUFACTURING COMPANY, A CORPORATION OF PENNSYLVANIA.

CONDENSER.

Application filed September 28, 1923, Serial No. 665,426. Renewed February 2, 1926.

To all whom it may concern:

Be it known that I, GEORGE BELL, a citizen of the United States, and a resident of Wilkinsburg, in the county of Allegheny and State of Pennsylvania, have invented a new and useful Improvement in Condensers, of which the following is a specification.

My invention relates to surface condensers and it has for an object the provision of apparatus of the character designated which shall deliver condensate to the hotwell at a high temperature, and which shall at the same time substantially eliminate re-evaporation of the condensate in the hotwell.

These and other objects and advantages of my invention are attained by the structure hereinafter described and illustrated in the accompanying drawing, in which Fig. 1 is a transverse sectional elevation of a condenser taken on the line I—I of Fig. 2; and Fig. 2 is a longitudinal sectional view of the condenser taken on the line II—II of Fig. 1.

Surface condensers of the so-called radial-flow type, shown and claimed in United States Patent No. 1,142,784, issued to Westinghouse Machine Company on June 8, 1915, on an application filed by Raymond N. Ehrhart, have the distinct advantage of providing a heat transmitting surface of high efficiency by reason of the large entrance area presented to the steam entering the tube nest, and the short path of travel of the air to the air off-take. This arrangement insures there will be no appreciable drop in pressure between the steam inlet and the point of complete condensation. Efficiency in the operation of condensers demands, in addition, that the energy expended in the withdrawal of the non-condensable fluids should be reduced to a minimum. This result is most readily accomplished by reducing the volume of fluids necessary to be handled by the air removing means prior to the delivery thereto, as disclosed in a copending application of Francis Hodgkinson, Serial No. 489,893, filed August 4, 1921, and assigned to the Westinghouse Electric and Manufacturing Company.

In the Hodgkinson application, the space traversed by the cooling tubes, and in which the condensation of steam is effected, is di-

vided into two compartments, which for convenience in description are therein termed a condensing chamber and an air cooling chamber, the latter overlying the hotwell of the condenser. The chambers are separated by hollow partitions which also serve to form passages connecting the chambers in series, the temperature and pressure within the air cooling chamber being relatively lower than that within the condensing chamber, due partly to the additional cooling effect produced therein and partly to its closer proximity to the air removal means. The above characteristic constructional features of the Hodgkinson application are in substance incorporated in the present application. In the Hodgkinson application, however, the hotwell is in open communication with the air cooling chamber, and the condensate discharged from the condensing chamber into the hotwell, consequently enters a region of relatively lower pressure and temperature and, under certain operating conditions, a slight re-evaporation takes place. The resultant vapors rise upwardly into the air cooling chamber and are recondensed, while the condensate assumes a lower temperature. A considerable heat loss is incident to this re-evaporation and recondensation.

In my apparatus, communication between the air cooling chamber and the hotwell is through a water or hydrostatic seal, while communication between the condensing chamber and the hotwell is open or direct. The temperature and pressure within the hotwell are therefore substantially equal to that of the condensing chamber of the condenser, which temperature and pressure are relatively higher than that of the air cooling chamber of the condenser. The comingling of the two liquids is therefore unproductive of re-evaporation and no cooling of the condensate is effected. Furthermore, passage of non-condensed gases from the condensing chamber to the cooling chamber is prevented. It follows from this construction, that the condensate removed from the hotwell is of the highest possible temperature consistent with that of the entering steam, an essential condition for obtaining high condenser efficiencies.

It is to be understood that my invention

does not relate solely to radial-flow condensers, but may be adapted to be employed with steam condensers of any type or design in which separate air and condensate removal means are provided.

Referring to the drawing for a more detailed understanding of an apparatus embodying my invention, I have indicated at 10 a condenser, having a shell 11 in which 10 there is a steam inlet 12, a hotwell 13, tube sheets 14 secured to the shell, and an eccentrically arranged nest of tubes 15 within the shell and secured to the tube sheets. Water boxes 17, joined to the tube sheets 15 and shell, are provided in the usual manner.

The tube nest is divided into two groups of tubes, which, for distinction and convenience in description, are hereinafter designated 20 as condensing tubes 20 and air cooling tubes 21. The air cooling tubes 21 constitute a wedge-shaped group rising from the bottom of the shell and having its base adjacent to the shell and above the hotwell. The edge of the wedge-shaped group is located well within the tube nest. The condensing tubes 20 surround the air cooling tubes except where the latter are adjacent to the shell 11.

30 The two groups of tubes are separated by suitable partitions or wall constructions extending the length of the condenser. As shown, these partitions are formed of inclined hollow wall members 22 and 23 comprising outer plate members 24, supported by means of continuous lugs 27 cast integral with the condenser shell, and inner plate members 25 secured to and spaced from the outer members 24 by suitable spacers 26. 40 The inner plate members 25 are spaced at their lower edges from the shell to form outlet passages and extend upwardly beyond the outer members 24. An air off-take 28 is carried by the inner plate members 25 and extends throughout the longitudinal length of the shell. It comprises a horizontal baffle portion 29 which covers the top of the air cooling chamber, and a hollow rectangular portion 31 having disposed therein 50 a plurality of rectangular openings 32 for the admission of the non-condensable gases. The non-condensable gases are removed from the air off-take by means of a plurality of conduits 33, which in turn communicate, through transformation pieces 34, with the air outlet flanges 35. The air outlet flange 35 is so designed as to make a fluid-tight joint with the condenser shell 11 and, at the same time, make a gas-tight joint with the transformation piece 34, thereby insuring complete separation of the air and the condensate. A baffle 36 is disposed horizontally above the air off-take 28, and extends 60 throughout the longitudinal length of the condenser shell. It prevents condensed fluid

or "rain" from falling into the hollow wall members 22 and 23 and being thereby conveyed to the air cooling chamber.

The hotwell 13 is bolted to a supporting flange 37 cast integral with the condenser shell 11. It comprises a central collection chamber 38 having communicating therewith two passages 39 for conveying condensate from the condensing chamber. Disposed centrally within the collection chamber 38 is a cup 41 cast integral therewith, and extending into the cup is a conduit 42 for conveying condensate from the air cooling and drying chamber. The conduit 42 has an extended flange portion 43, which is bolted to the upper face of the hotwell and makes a gas tight joint therewith, the conduit 42 and the cup 41 forming a water or hydrostatic seal through which all condensate discharged from the air cooling chamber must pass. Condensate which accumulates in the collection chamber 38 is discharged through an outlet port 44 provided in the bottom of the hotwell.

20 In some instances, circulation of condensate through the hotwell may be facilitated by venting the collection chamber of the hotwell into the air cooling and drying chamber. This may be accomplished by providing a small hole or restricted opening 43' between the two chambers.

Having thus described the arrangement of an apparatus embodying my invention, the operation thereof is as follows: Steam from a turbine, or other prime mover, is admitted into the condensing chamber through the steam inlet 12 and passes within the shell in such manner as to substantially surround the cooling tubes within the condensing chamber. The cylindrical entrance area to the tube nest is enabled to accommodate large volumes of steam readily, and the steam passes radially through the nest of tubes toward the inlet ends of the passages 22 and 23 at approximately a central point within the tube nest. The steam is almost completely condensed in the passage over the tubes so that non-condensable gases having a small condensable fluid content pass between the walls 24 and 25 to the lower portion of the air cooling chamber. The air flows upwardly through the air cooling chamber over the cooling tubes, which contain first-pass cooling water, and is further dried and cooled. The condensate dripping from the cooling tubes of the chamber falls into the hotwell, wherein it mingles with the condensate from the condensing chamber as will be hereinafter more fully described. The air then enters the inlet ports 32 of the air off-take 28, passes to the conduits 33, and is withdrawn through the air outlet flanges 35 by any suitable pump.

100 The condensate collects in the bottom of the condensing chamber adjacent to the lugs

- 27 and the baffles 24, and is conveyed therefrom through the passages 39 to the collection chamber 38 of the hotwell. Condensate within the air cooling chamber falls 5 into the conduit 42 and passes through the seal formed by the conduit and the cup 41, into the collection chamber 38 wherein it mingles with the condensate from the condensing chamber. The cup 41 is filled with 10 condensate at all times during operation, and, as indicated on the drawing, a leg of water having a slightly higher level than the top of the cup will be maintained in the conduit 42 because of the relatively higher 15 pressure prevailing within the condensing chamber. This hydrostatic seal prevents a flow of non-condensable gases from the condensing chamber back through the hot well into the air cooling chamber. It further insures that the temperature and pressure prevailing within the collection chamber 38 of the hot well will be substantially 20 those of the condensing chamber. It follows, that the flow of condensate from the 25 air cooling chamber to the hotwell, which is a region of relatively higher pressure will not be conducive to re-evaporation. The mingled condensate is removed through the outlet port 44 by any suitable pump.
- 30 While I have shown my invention in but one form, it will be obvious to those skilled in the art that it is not so limited, but is susceptible of various other changes and modifications, without departing from the 35 spirit thereof, and I desire, therefore, that only such limitations shall be placed thereupon as are imposed by the prior art or as are specifically set forth in the appended claims.
- 40 What I claim is:
1. In a condenser, the combination with a shell having a fluid inlet port, of a nest of air cooling tubes contiguous to the bottom of the condenser, a nest of condensing tubes at the sides of and above said air 45 cooling tubes, partition means defining air passages between said groups of tubes, means for removing condensed fluid from the condensing tubes, and means including a fluid seal for removing condensed fluid 50 from the air cooling tubes.
  2. In a condenser, the combination with a shell having a fluid inlet port and a nest of cooling tubes within the shell, of an air cooling and drying chamber within the shell 55 through which a portion of the cooling tubes extend, the remaining tubes traversing a condensing chamber, partition means between the chambers comprising passages through which the uncondensed fluids pass 60 from the condensing to the air cooling chamber, means for removing condensate from the condensing chamber, and means for removing condensate from the air cooling chamber, said last mentioned means including a hydrostatic seal.
  3. In a condenser, the combination with a shell having a fluid inlet port and a nest of cooling tubes within the shell, of an air cooling chamber within the shell through 70 which a portion of the cooling tubes extend, the remaining tubes traversing a condensing chamber, partition means between the chambers comprising passages through which the uncondensed fluids pass from the condensing to the air cooling chamber, a hotwell, means for withdrawing condensate from the condensing chamber to the hotwell, means including a fluid seal for conveying condensate from the air cooling chamber to 75 the hotwell, and condensate outlet means provided in the hotwell.

In testimony whereof, I have hereunto subscribed my name this Sept. 13, 1923.

GEORGE BELL.
